UNITED STATES PATENT OFFICE

HERBERT D. CLEMMONS, OF STURGIS, MICHIGAN, ASSIGNOR TO SCOVILL MANUFACTURING COMPANY, OF STURGIS, MICHIGAN

DESIGN FOR A BALL COCK BODY

Application filed April 28, 1932. Serial No. 43,641. Term of patent 14 years.

To all whom it may concern:

Be it known that I, HERBERT D. CLEMMONS, a citizen of the United States, residing at Sturgis, in the county of St. Joseph and State of Michigan, have invented a new, original, and ornamental Design for Ball Cock Body, of which the following is a specification, reference being had to the accompanying drawing, forming part thereof, in which—

Fig. 1 is a side elevation,

Fig. 2 an elevation looking from the left of Fig. 1,

Fig. 3 an elevation looking from the right of Fig. 1 of a ball cock body, showing my new design, and

Fig. 4 is a perspective view looking down from the top.

I claim:

The ornamental design for a ball cock body, as shown.

HERBERT D. CLEMMONS.
